UNITED STATES PATENT OFFICE.

JOHN A. SECOR, OF NEW YORK, N. Y.

EXPLOSIVE-ENGINE.

SPECIFICATION forming part of Letters Patent No. 623,568, dated April 25, 1899.

Application filed November 10, 1898. Serial No. 696,016. (No model.)

To all whom it may concern:

Be it known that I, JOHN A. SECOR, a citizen of the United States, residing in the borough of Brooklyn, city of New York, State of New York, have invented certain new and useful Improvements in Explosive-Engines, of which the following is a specification, reference being had to the accompanying drawing, forming a part thereof.

- 10 This invention relates to explosive-engines in which the hydrocarbon, which forms the basis of the explosive mixture, is delivered in a liquid form and is introduced into the working cylinder of the explosion-chamber after each explosion in a quantity sufficient to form the next charge, the hydrocarbon being vaporized within the working cylinder. The hydrocarbon or oil is commonly delivered by a force-pump, the stroke of which is varied to increase or diminish the quantity of oil supplied. It has also been proposed to deliver the oil by gravity. The desirability of providing for a uniform delivery of the oil at least to the point where the engine-governor 25 regulates the delivery in order that the speed of the engine shall not be subject to variations has been generally recognized. Experience has shown, however, that the various methods hitherto employed of feeding the oil 30 by gravity have failed to provide for an absolutely unvarying and uniform head. In all of such cases, so far as I am aware, the oil has been delivered from closed tanks under pressure or from closed tanks from which the oil 35 escapes from time to time as the delivery-openings of the tanks are uncovered by the withdrawal of oil from another vessel, and air is admitted to the closed vessels to displace the oil therein. Without complicated, 40 delicate, and expensive devices it is impossible to maintain absolutely uniform pressure upon the oil in the closed vessels, and in the other class of devices referred to it is obvious that the level of the oil outside of the closed 45 vessels must change sufficiently to at least cover and uncover the delivery-orifice of the closed vessel. In view of the very small quantity of oil used at each explosion it is evident that even the slight variations of pressure or 50 head thus occasioned will produce a relatively great change in the quantity of oil actually

delivered and will effect the operation of the engine to a corresponding degree.

It is the object of this invention to provide for the maintenance of the oil in the delivery vessel at an absolutely uniform level and under the same pressure at all times, the conductor between such delivery vessel and the engine remaining always open and the flow of oil therethrough being regulated as the load upon the engine varies by the engine-governor. The devices by which this result is secured will be more fully described hereinafter with reference to the accompanying drawing, which represents, partly in elevation and partly in vertical section, an engine to which the invention is applied.

The crank-shaft C, cylinder E, piston-rod F, inlet and exhaust valves h and h' , and their actuating devices—such as the links i^2 , levers i^3 , and cam-gear I—may all be constructed, arranged, and operated as usual or as preferred.

A suitable vessel K, having a considerable capacity and serving as the main or supply vessel, is supported at a suitable height above the cylinder, so as to insure a proper flow of the oil. It may have a conical bottom k with a draw-off cock at the apex to facilitate the withdrawal of any sediment that there may be in the vessel. At a proper distance above the bottom is a feed-pipe k^2 , which is arranged to conduct the oil to a second vessel L, the said pipe being provided with a needle or other suitable valve of ordinary construction, (indicated at k^3), the said valve being controlled by a float k^4 , which rests upon the oil in the second or delivery vessel L. Both of the vessels K and L are open to atmospheric pressure, although the oil therein may be protected from dust and other foreign substances by any suitable means. The delivery-pipe l communicates with the delivery vessel L at a suitable height above its bottom and with the engine at a point slightly in advance of the inlet-valve h , preferably in the inlet-pipe h^2 , between the air-valve M and the inlet-valve h . A sight-glass may be inserted in the delivery-pipe, as at l' , to permit the flow of the oil to be observed. The delivery-pipe is at no time closed between its extremities, although the flow of the oil therethrough

may be regulated, according to the load upon the engine, by a suitable valve, as at M', the two valves M and M' being connected together, but with capacity for independent adjustment, and controlled through suitable intermediate mechanism (represented by a lever n^6 and link n^7) by a suitable governor mechanism, (indicated at N.)

It will be observed that as the oil in the two vessels K and L is always under atmospheric pressure, which is practically constant, and as by the float valve described the level of the oil in the delivery vessel L is maintained at a constant height the oil in the delivery-pipe is always under a constant head and its flow is uniform, except as it is changed with a change of load upon the engine. Under given conditions of work, therefore, the flow of oil is constant and uniform, and for each period of time represented by the complete cycle of the engine a uniform quantity of oil is delivered. In the operation of the engine represented the oil falling into the air-inlet pipe h^2 is struck by the strong blast of air passing through the same during the charging stroke of the engine and is immediately converted into spray and carried through the inlet-valve h into the working cylinder of the explosion-chamber of the engine, where it is vaporized and mixed with the air to form the fresh charge. It will be evident that by reason of the termination of the delivery-pipe at a point in front of or outside of the inlet-valve h the flow of the oil is not affected by the pressures developed within the working

cylinder, and it is therefore possible to supply and deliver the oil from vessels open to atmospheric pressure.

I claim as my invention—

1. The combination with an explosive-engine, of a delivery vessel, a pipe communicating with said delivery vessel and also having an unobstructed entrance at its opposite end into the air-inlet of the engine, said vessel being open to atmospheric pressure, a supply vessel also open to atmospheric pressure and communicating with the delivery vessel, a valve in the communication between said vessels, and a float in the delivery vessel to control said valve; substantially as shown and described.

2. The combination with the air-inlet, inlet-valve and valve-operating mechanism of an explosive-engine, of an oil-supply vessel and an oil-delivery vessel open to atmospheric pressure and communicating the one with the other, a valve in the communication between said vessels, a float in the delivery vessel to control said valve, and a delivery-pipe from said delivery vessel having an unobstructed entrance into said air-inlet in advance of the inlet-valve, substantially as shown and described.

This specification signed and witnessed this 3d day of November, A. D. 1898.

JOHN A. SECOR.
